THÉOPHILE CAUX, OF LAWRENCE, MASSACHUSETTS

DRAWING-IN-FILLING PREVENTER

Application filed September 26, 1928. Serial No. 308,549.

This invention relates to improvements in looms, and it consists of the constructions, combinations and arrangements herein described and claimed.

5 An object of the invention is to prevent the catching of the remaining filling on a bobbin between the shuttle and box plate of a loom and the breaking off thereof at the moment of the transfer of a new bobbin from the magazine, thus to prevent an end of filling being left between the box plate and shuttle to be worked into the cloth on the next pick.

10 Another object of the invention, and one which naturally follows the foregoing statement, is to prevent the occurrence of what is known as drawing-in filling in the operation of any magazine loom.

15 A further object of the invention is to provide a box plate having a wall which is movable by a finger attached to a part of the trans- 20 ferrer of a magazine loom of the Draper type, the purpose of moving the wall being to avoid the hanging and breaking off of the end of the filling on the spent bobbin as said bobbin is 25 ejected by a fresh bobbin introduced from the magazine by said transerrer.

Other objects and advantages appear in the following specification, reference being had to the accompany drawings in which

30 Figure 1 is a cross section of enough of the magazine and the associated parts of a Draper loom to illustrate the application of the improved box plate,

35 Figure 2 is a perspective view of the improved box plate as applied to a shuttle box,

Figure 3 is a plan view thereof,

Figure 4 is a horizontal section there- 40 through, showing parts that are obscure in Figure 3, more clearly,

45 Figure 5 is a detail sectional view illustrating the action of the transerrer.

Figure 6 is a detail perspective view of the actuating finger which is attachable to a part of the transerrer.

50 As stated in the introduction to this description the invention is applicable to any magazine loom of which the Draper and Northrop are representative types. This type of loom has a transerrer which is periodically brought into operation by the filling

stop-motion to press a fresh bobbin into the shuttle and at the same time push the spent bobbin out of the bottom of the shuttle which is open for the purpose.

55 It has been known to happen that the end of the spent filling will get caught between a part known as the box plate and the shuttle so that when the spent shuttle is pushed out a piece of the filling will break off and remain in place between the box plate and shuttle. Upon the occurrence of the next pick this broken portion of filling will be worked into the cloth giving the cloth a thick, heavy and objectionable appearance at this particular point. An occurrence such as this is 60 known as drawing-in filling.

65 Such portions of a known structure with which the improvement is concerned are briefly described as follows:—A transerrer 70 1, pivotally mounted upon a stub shaft 2 carried by a bracket 3 on the frame 4 of the loom has an arm 5 with which a latch finger 6 is pivotally connected. The latch finger has a projection 7 which is adapted to be engaged by the bunter 8 of the lay 9 as the latter comes 75 forward. This act causes the transerrer to push a fresh bobbin of filling B from the magazine 10 into the shuttle 11 which occupies a position in the shuttle box 12.

80 The shuttle box is defined by a pair of box plates which are substantially identical with the rear member designated by the numeral 12 in Figure 1. The shuttle is open at the top and bottom, respectively for the admission of a fresh bobbin and the discharge of a spent 85 bobbin. The open bottom communicates with a chute 13 which leads into a bobbin receptacle 14.

85 The improvement resides, first, in the shuttle box. The front box plate which, ordinarily, would be substantially like the member 12 is replaced by a box plate 15 of a structure as shown in Figures 2 and 3 for example. The outstanding feature of this box plate is a yieldable or movable portion or side 16. 90 This portion does not necessarily extend full length of the box plate but, according to the present showing, occupies the major central part only, as well shown in Figures 2, 3 and 4. This side is carried by a pin 17 which is 100

let into the side by way of a groove 18 adjacent to a bearing boss 19 at one end of the box plate. The opposite end of the pin fits into a somewhat similar bearing boss 20. The side 16 is capable of being rocked upon the pin 17 as a hinge, and when rocked will release the end of the spent filling which might otherwise become wedged between the shuttle and the box plate.

In providing for the movable side 16, the box plate 15 is recessed at 21 so that the side may fit in and comprise a substantial continuation of the face of the box plate. The wall 22 which defines the front side of the recess, connects the bosses 19 and 20, and has a formation at 23 to which the pivot screw 24 of a lever 25 is secured. The inner end of the lever is shaped down like a finger 26 to work between a projection 27 and the adjacent surface of the movable side 16. The outer end of the lever is broadened out like a plate 28 to provide an adjacent bearing for an actuating finger 29.

This finger is secured to the latch finger 6 by the same nut and bolt 30 which ordinarily secures the projection 7 to the latch finger. The actuating finger has a slot 31 to receive the bolt, and to permit certain necessary adjustments as to position. The foregoing forward motion of the lay, at which time the bunter 8 will engage the projection 7, also brings the plate 28 of the lever 25 into engagement with the actuating finger 29, so that the lever is rocked upon its pivot 24 and the side 16 caused to move forwardly upon its hinge pin thus enlarging or making more room in the shuttle box or, in other words, to release the end of the spent filling if caught.

A spring 32 (Fig. 4) tends to keep the movable side 16 in an original position. The action of the spring in one direction is limited by the engagement of a stop 33 on one end of the side, with a part of the box plate 15 directly beneath the bearing boss 20. The box plate has bifurcated lugs 34 by which it is attached to the lay beam 9 by studs ordinarily provided for the purpose.

A facing of leather 35 on the inside of the box plate frictionally receives the shuttle. The leather facing covers the inner face of the box plate, including the movable side 16, and may be continuous. But according to the showing in Figure 4, portions of the leather facing are cut at 36 so that the leather may be individually fastened to adjoining ends of both the rigid box plate 15 and the movable side 16. This arrangement is preferable because by means of it the lower portion of the leather facing will be made to bend with the movable side. If the leather were uncut at 36, that is to say continuous, there would simply be a release of the pressure when the movable side is displaced by

means of the lever 25. Either arrangement would serve the purpose.

The ends of the leather facing are fastened to the extremities of the box plate at 37. The leather is drawn well over the ends of the box plate, and the fastening means 37 introduced well out of the way of the working face. By carrying one end of the leather around and in front of the groove 18, the leather is made to serve as a closure for that groove. Ordinarily it would not be possible for the pin 17 to work out of the groove 18, but should there be any such tendency, the leather facing would act as a preventative.

The operation is readily understood. Figure 5 illustrates the act of pressing a full bobbin B into the shuttle 11 by means of the transerrer 1. The spent bobbin B' has been pushed out, but an end of the filling f still occupies the eye e of the shuttle. In cases where the sides or plates of the shuttle box 12 are solid and rigid it often happens that the remaining end of the filling will catch or wedge between the shuttle 11 and the shuttle box, so that when the fresh shuttle B comes in, the end of the filling f becomes broken off and remains in its wedged position.

This broken off piece of filling will work into the cloth on the next pick and produce an objectionable defect. According to the invention it is proposed to prevent the wedging of the end of the filling f in the manner stated. This is done by releasing one plate 100 of the shuttle box.

As the lay 9 moves forward, that is to say, toward the left in Figure 1, the bunter 8 will operate the latch finger 6 to in turn operate the transerrer 1. At the same time, the plate 28 of the lever 25 will engage the actuating finger 29, which is conveniently attached to the latch finger 6, causing a rocking of the lever and an ultimate rocking of the movable side 16 of the improved box plate 15. By moving the side 16 there will be an immediate release of the end of the filling f as shown in Figure 5, so that as the spent bobbin B' drops down into the chute 13, the filling will unthread from the eye e and leave the shuttle box unobstructed.

While the construction and arrangement of the improved filling drawing-in preventer is that of a generally preferred form, obviously modifications and changes may be made without departing from the spirit of the invention or the scope of the claims.

I claim:—

1. A filling drawing-in preventer for looms, comprising a shuttle box having a portion of the inner face of one side wall movably mounted and forming a check for the shuttle, and means by which the said portion is moved outwardly to enlarge the shuttle box upon the transfer of a fresh bobbin.

- from the magazine of the loom to a shuttle in the shuttle box, thereby preventing the trailing end of a spent filling from being wedged between the shuttle and shuttle box.
5. 2. A filling drawing-in preventer for looms comprising a shuttle box having a recess in one side wall, a plate movably mounted in the recess and forming a portion of said wall, and means to move said plate forward 10 the rear wall of the recess thereby enlarging the shuttle box upon the transfer of a fresh bobbin from the magazine into a shuttle in the shuttle box.
- 15 3. A filling drawing-in preventer for looms comprising a shuttle box having a recess in one side wall, a plate movably mounted in the recess, means tending to keep the plate in a position flush with the working face of the side of the shuttle box, and means 20 to move said plate out of said position into the recess upon the transfer of a fresh bobbin from a magazine into a shuttle in the shuttle box.
- 25 4. A filling drawing-in preventer for looms comprising a shuttle box having a recess in one side wall, a plate rockably mounted in the recess, means tending to keep the plate in a position flush with the working face of the shuttle box, a lever for rocking 30 said plate, and means with which the lever is engageable upon the transfer of a fresh bobbin from a magazine into a shuttle in the shuttle box, causing a recession of the movable plate and the release of an end of the 35 filling on a spent bobbin displaced from the shuttle by said fresh bobbin.
5. A filling drawing-in preventer for looms comprising a shuttle box, a movable plate which forms a part of the shuttle box, 40 a projection carried by the said plate, a pivoted member on the shuttle box and engaging the projection, and an actuating finger carried by a portion of a loom and engaging the pivoted member to move the plate outwardly 45 upon the transfer of a fresh bobbin from a magazine into a shuttle in the shuttle box.
6. In a device of the character described, a member forming one side of the shuttle box and having a recess therein, a plate hinged in the recess, and a lever pivoted upon a wall of the recess and having engagement with the plate for moving it upon said hinge.
- 55 7. In a device of the character described, a member forming one side of a shuttle box and having a recess therein, a plate hinged in said recess, a projection on the plate, a spring fitted between a wall of the recess and said plate tending to press the plate out of 60 the recess, a stop on the plate engaging a portion of the said member limiting the action of the spring and keeping the plate flush with the working face of the member, and a lever pivoted on said member and engaging said 65 projection and being capable of moving the plate upon its hinge against the action of the spring.
8. In a device of the character described, a member forming one side of a shuttle box and having bearing bosses and a connecting wall defining a recess, a plate situated in the recess, a pin by which the plate has a hinge mounting upon said bosses, and a lever pivoted upon the member and having connection with the plate to move the same upon its hinge mounting.
- 70 9. In a device of the character described, a member forming one side of a shuttle box and having bearing bosses and a connecting wall defining a recess, said member having a groove from one end to an adjoining bearing boss, a movable plate situated in the recess, and a pin introduced through said groove into the bearing bosses and through 75 portions of the plate to provide a hinge mounting.
- 75 10. In a device of the character described, a member forming one side wall of a shuttle box and having bearing bosses and a connecting wall defining a recess, said member having a groove from one end to an adjacent bearing boss, a movable plate situated in the recess, a pin introduced into the plate and bearing bosses through said groove, and a facing applied to the member and plate 80 and carried around the ends of the member to close the groove and prevent the pin from working out.
- 85 11. In a device of the character described, a member forming one side of a shuttle box and having a recess, a plate movably mounted in the recess, a facing applied to the working face of the member and plate, said facing being cut at points adjoining the ends of the plate and ends of the recess, and means by which the facing is attached to the extremities of the member and at said cut points, permitting yielding of a portion of the facing when said plate is moved.
